UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

TURBINE.

SPECIFICATION forming part of Letters Patent No. 769,612, dated September 6, 1904.

Application filed August 21, 1902. Serial No. 120,477. (No model.)

To all whom it may concern:

Be it known that I, OSCAR JUNGGREN, a citizen of the United States, residing at Schenectady, county of Schenectady, State of New York, have invented certain new and useful 5 Improvements in Turbines, of which the following is a specification.

It has been proposed to provide turbines with governors which are inclosed in the 10 wheel-case in order to protect them from injury, particularly where the turbines are used to drive dynamo-electric machines arranged to supply current to locomotive-headlights. All of the turbines of this class with which I 15 am familiar are provided with complicated governors which have a great many moving parts and bearing-surfaces and are so arranged that it is impossible to inspect them without taking down the turbine to a considerable extent.

My invention has for its object to so arrange the turbine and the governor parts that the complex mechanism usually employed is obviated and the turbine and governor parts 25 rendered reasonably accessible.

For a consideration of what I consider to be novel and my invention attention is called to the specification and claims appended hereto.

In the accompanying drawings, which represent an embodiment of my invention, Figure 30 1 is a vertical section of a turbine. Fig. 2 is a vertical section of the governor. Fig. 3 is a plan view of one of the governor-weights, and Fig. 4 is a cross-section of the inlet-valve for 35 controlling the passage of fluid to the turbine.

1 represents the outer casing of the machine, which is provided with a base 2 and an exhaust-passage 3, the latter opening into the under side of the casing in such a manner 40 that the water due to condensation will be drained therefrom. The upper surface of the casing is turned true to receive the cover 4. The latter is made in two parts, and these are bolted to the base. To the smaller part of 45 the cover is detachably secured by screws or bolts the nozzle 5, the latter being of any suitable construction. I find it desirable, although not necessary, to make this nozzle of the expanding type, since it has many advantages.

The smaller cover-section is bolted to the 50 larger and also to the wheel-casing 1. By such a construction the nozzle can readily be removed for the purpose of inspection or repair, and when removed the interior of the casing can be inspected to a certain extent. 55 Rotating the wheel in front of the opening affords an opportunity to inspect the buckets on the wheel. The other or main part of the cover carries the admission-valve 6 and has a fluid-carrying conduit or passage 7, that opens 60 into a similar conduit 8, formed in the other or smaller part of the cover, and the latter discharges into the nozzle 5. Situated above the valve and detachably secured to the cover by bolts is a plate 9, containing a conduit, one 65 end of which is in communication with the main valve and the other with the inlet-pipe. Removing the plate gives access to the valve, which is directly below it and in line with the 70 axis of the wheel.

Mounted for movement within the casing is a wheel 10, having a plurality of buckets 11, arranged in rows. The number of buckets in a row and the number of rows can be varied to suit the different conditions of service. In 75 so far as the construction of the casing and that of the governor mechanism is concerned it is obvious that the particular structure of the motive-power elements is immaterial. Located between the rows of revolving buckets 80 are other and stationary buckets 12, commonly known as "intermediates." These are mounted on a support which is bolted to the turbine-casing and can readily be removed.

The bucket-wheel is mounted on the end of 85 the upright shaft 13 and is seated on a shoulder formed thereon. The shaft is shown in a vertical position; but it is to be understood that the turbine and governor will operate equally well in a horizontal position. Being in a vertical 90 position, a step-bearing (not shown) is provided for the lower end of the shaft. The base is provided with a raised portion having an inclined top and an enlarged opening, and mounted in the opening is a flanged disk 14, 95 which surrounds the shaft and forms a part of a packing-ring for preventing steam from escaping from the casing or for maintaining

a vacuum. The disk is held in place by a number of angularly-spaced bolts and projects slightly above the raised portion, so as to prevent the collection of water at this point. In 5 the disk is a chamber containing packing, and the latter is compressed by the gland 15, the said gland being adjustably secured by bolts. The top of the disk 14 is inclined or beveled, so that the water due to condensation will be 10 carried over the raised portion of the base into the exhaust-conduit. Situated below the packing-ring and carried by the base is a steady bearing 16 of any desired construction. The packing ring and gland and also the 15 steady bearing are accessible through a hole 17 in the side of the base. The casing is provided with an extension or subbase 18 and is prevented from moving laterally by a flange or projection 19, formed on the under side. 20 The support for the subbase 18 may be a part of a dynamo or other apparatus to be driven.

Steam on being admitted to the turbine passes through the nozzle into the passages formed between the buckets on the wheel and 25 intermediate. This action imparts rotary motion to the wheel, and the exhaust passes out of the conduit 3 in any suitable receptacle, such as a second stage or into a condenser.

Situated in the detachable cover and so positioned that it can regulate the passage of steam through the conduit 7 is the sliding throttle-valve. It comprises a tubular casing or steam-chest, which can be withdrawn from above and has ports 20, that are arranged to 30 be covered or uncovered by the piston-valve 21. The valve is detachably secured to a stem 22, that extends parallel and in line with the axis of the main shaft. By removing the plate 9 the valve can be removed without disturbing the remainder of the turbine or governor. The piston-valve is provided with 35 openings which extend parallel with the stem, and therefore the high-pressure steam acts on both ends. The valve is practically balanced; but owing to the valve-stem being attached to its under side the area of the upper side is 40 slightly greater than that of the lower or under side. I utilize this difference in area to overcome friction and to cause the valve to 45 move downward whenever it is permitted to do so by the governor. The valve-rod is provided with a long bearing in the cover, which effectively prevents steam from leaking from the conduit into the wheel-chamber. The 50 governor is mounted directly on the end of the main shaft, and I employ the base thereof as a nut to secure the wheel in place.

Referring particularly to Fig. 2, 23 represents the base of the governor, having a screw-threaded opening at its lower end to receive the main driving-shaft and a spring-receiving opening at the other. The compression-spring 24 is seated on a shoulder formed on the base and tends at all times to push the thimble 55

outward. The thimble has a finished exterior and is guided in its movements by the cylindrical wall of the base. On the end of the thimble and in line with the valve-stem 22 is a projection 26, which as it engages with the stem moves it in a manner to vary the admission of steam to the nozzle. Situated on opposite sides of the governor-base and secured thereto are arms 27, which are connected at their outer ends by a detachable piece. These arms are arranged to support the moving weights, and the end pieces are provided with grooves 28 to receive the knife-edges on the weight-arms. Each weight-arm is provided with a knife-edge 29, which engages with a groove 28 in an arm 27. On the ends of the 70 arms are heavy weights 30, which are curved so as conform to the curvature of the base. On the weight-arm and at a point between the weights and preferably above the knife-edge 75 29 is a projection 31, formed integral therewith. In the end of each projection is mounted a roller 32, which engages with the end of the thimble and causes it to move up or down as the speed of the wheel changes. It should be noted that the knife-edge pivots for the 80 weighted arms are nearer one weight than the other. By using two weights and mounting them as described one of the weights must move inward toward the center of revolution while the other moves outward. Obviously 85 the one exerting the greater leverage will overcome the other. In the present instance the lower weights exert the greater effort. The construction described is a very advantageous one, since it permits me to use a relatively 90 short spring 24, while attaining all of the benefits of heavy weights. It also enables me to make the parts small and compact and of simple construction.

In order to prevent excessive wearing of 95 the moving parts, the slotted arms containing the grooves can be hardened as well as the knife-edges themselves. The thimble and rollers can also be hardened, if desired. The 100 governor acts directly on the valve-stem without the intervention of any levers whatsoever. Hence the mechanical simplification over ordinary governors is marked. It is also inclosed 105 so as to be fully protected from injury, and as the turbine is more especially intended for 110 use in connection with electric headlights for locomotives where it is exposed the usefulness 115 of such an arrangement is apparent. The governor being situated in the wheel-chamber, which is at all times filled with low-pressure 120 steam when the turbine is running, will be well lubricated by the water due to condensation.

In accordance with the provisions of the patent statutes I have described the principle of 125 operation of my invention, together with the apparatus which I now consider to represent the best embodiment thereof; but I desire to

have it understood that the apparatus shown is only illustrative and that the invention can be carried out by other means.

What I claim as new, and desire to secure 5 by Letters Patent of the United States, is—

1. In a turbine, the combination of a wheel, a casing therefor, a valve for controlling the admission of fluid to the wheel, which is directly in line with the wheel-axis, a governor 10 which is completely inclosed by the wheel-casing for actuating the valve, and a conduit for conveying the fluid from the valve to the periphery of the wheel.

2. In a turbine, the combination of a wheel-casing, a detaching cover for the casing, a valve for controlling the turbine mounted in the cover and directly in line with the axis of the wheel, a wheel, and a governor actuated by the wheel for adjusting the valve which is 15 situated between the cover and the wheel in the steam-space of the casing.

3. In a turbine, the combination of a bucket-wheel, a casing therefor, a cover for the casing, a valve controlling the admission of fluid 20 to the wheel which is mounted in the cover and in line with the wheel-axis, a governor mounted on the end of the wheel-shaft between the wheel and cover, and a stem extending into the cover which actuates the 25 valve and is itself moved by the governor.

4. In a turbine, the combination of a wheel, a casing therefor, a valve which is situated within the casing in line with the shaft of the wheel, a governor which is within the casing 30 and in contact with the low-pressure fluid from the wheel, and a driving connection between the governor and the wheel.

5. In a turbine, the combination of a bucket-wheel, a shaft therefor, a governor mounted 35 on the shaft engaging with and holding the wheel in place, and a casing which incloses the bucket-wheel and the governor.

6. In a turbine, the combination of a wheel, a casing therefor, a two-part detachable cover, 40 an admission-valve carried by one of the parts, and a nozzle which delivers fluid to the wheel and is carried by the other part of the cover.

7. In a turbine, the combination of a wheel, a casing therefor, a two-part detachable cover, 45 a nozzle for delivering motive fluid to the wheel which is detachably secured to the cover, and an admission-valve which is wholly carried by one part of the cover.

8. In a turbine, the combination of a wheel, 50 a casing therefor having a raised interior portion with a slanting top, a vertical shaft for the wheel which passes through said raised portion, a stuffing-box for the shaft which extends above the raised portion of the base to

prevent the accumulation of water, and an exhaust-conduit leading out of the casing from a point below said raised portion. 60

9. In a turbine, the combination of a wheel, a casing therefor having a raised portion which surrounds the shaft of the wheel and has an inclined top, a stuffing-box which surrounds the shaft and is carried by said raised portion, and a steady bearing which is carried by the base of the casing. 65

10. In a turbine, the combination of a wheel, 70 peripheral buckets therefor, an expanding nozzle for discharging fluid against the buckets in the form of a jet under high velocity, a governor attached to the end of the wheel-shaft, a valve controlling the supply of fluid 75 to the nozzle, a means moved axially by the governor for moving the valve, and a casing that is common to the governor and valve, which incloses and protects them from injury.

11. In a rotary engine, a stationary casing, 80 a steam-driven wheel mounted therein, a steam-inlet centrally located in one side of said casing, a steam passage-way leading from the inlet and discharging against the wheel, and means driven by the wheel and within the 85 casing for controlling the admission of steam through said inlet.

12. In a rotary engine, a stationary casing, 90 a steam-driven wheel mounted therein, a valve-receiving chamber centrally located in one side of said casing through which the steam enters the casing, a slide-valve for regulating the passage of steam through said chamber, and means within the casing and actuated by the wheel for controlling the movements of 95 said valve.

13. In a rotary engine, a casing formed of two members or halves secured together, a wheel mounted therein, a steam passage way 100 leading from a central portion of one member to a point between said members, and a nozzle communicating with the outlet end of said passage which discharges steam against the wheel.

14. In a rotary engine, the combination of a casing, one side of which is detachable, a 105 valve for controlling the engine mounted in the detachable side of said casing and directly in line with the axis of the wheel, a wheel, and a governor actuated by the wheel for adjusting the valve, said governor being located 110 between the wheel and the detachable portion of the casing.

In witness whereof I have hereunto set my hand this 4th day of August, 1902.

OSCAR JUNGGREN.
